OSCAR ROESEN, OF NEW YORK, N. Y., ASSIGNOR TO R. HOE AND CO., OF NEW YORK, N. Y.,
A CORPORATION OF NEW YORK.

FOLDING AND DELIVERING MECHANISM.

1,258,708.

Specification of Letters Patent. Patented Mar. 12, 1918.

Application filed April 8, 1916. Serial No. 89,745.

To all whom it may concern:

Be it known that I, OSCAR ROESEN, a citizen of the United States, residing at New York city, county of New York and State 5 of New York, have invented certain new and useful Improvements in Folding and Delivering Mechanism, fully described and represented in the following specification and the accompanying drawings, forming a 10 part of the same.

This invention relates to certain improvements in folding and associating mechanism for printing machines.

In printing mechanisms of certain constructions, as, for instance, a press in which the form cylinders are provided with plates six pages across the cylinders and four pages around, the full capacity of the press cannot be utilized for the production of certain products, as, for instance, products having sixteen pages, without the use of two folders. This use of such presses is desirable for the large production of such small products. The use of two folders, however, 20 requires double mechanism for operating them, and when it is desired to add a cover or an insert to the product, separate cover and insert feeding mechanisms for each folder and delivery is necessary. Such 25 double folding and feeding mechanisms therefore require a machine of complicated construction, both expensive to build and to operate.

It is one object of the present invention 30 to produce an improved folding and associating mechanism whereby the full capacity of a press such as is above referred to may be utilized in producing small products of sixteen pages with a single folder.

It is a further object of the invention to 35 produce such a folding and associating mechanism, including a single folder or delivery, which is compact and which can be arranged to coöperate with the usual number of cover and insert feeding mechanisms where they are employed, so that the 40 number of such cover and insert feeding mechanisms does not have to be increased.

For a full understanding of the invention, 45 reference may be had to the accompanying drawings, in which—

Figure 1 is a side elevation of so much 50 of a printing machine as is necessary for an understanding of the invention, certain 55 parts being broken away;

Fig. 2 is a front elevation, partly in section, of the folding mechanism, the mechanism shown being arranged for use with sheets cut two pages long;

Fig. 3 is an end view of the folding mechanism shown in Fig. 2, certain parts being shown in section, showing the grippers and operating cams in position to fold off at each revolution at one end of the folder;

Fig. 4 is a view similar to Fig. 3, showing the parts in position to fold off at every other revolution at the other end of the folder;

Fig. 5 is a detail plan view of the cam operating mechanism for operating the folding-off mechanism; and

Fig. 6 is a detail showing how the webs are run through the machine where three webs or ribbons are employed.

The particular machine illustrated in the drawing is capacitated to produce products from a web printed six pages wide and four pages around the cylinder, forty-eight pages being printed at each revolution of a printing couple, and for producing a product of sixteen pages, though it will be understood that other products may also be produced and from a machine printing a different number of pages. In the present instance, when forty-eight pages are printed 50 at one revolution to produce full capacity of sixteen, this web will be slit into three ribbons each two pages wide, and in the machine illustrated two of these ribbons will be superposed in the usual manner by 55 suitable turner bars 1, and the double and single ribbons will be forwarded side by side through the machine over a guide-roll 2. Suitable forwarding devices are employed, and in machines embodying the invention in its preferred form, and as shown in Figs. 1 to 6, the webs will be cut into sheets at the half turn, that is, each sheet will be two pages wide and two pages long, so that at each cutting operation a product 60 of sixteen pages will be formed from the superposed webs and a product of eight pages from the single web. Cutting mechanism of the usual type may be employed, which in the particular instance acts to forward the webs, such as cutting cylinder 3 65 coöperating with a cutter block carrying cylinder 4.

After the sheets are cut from the webs they are forwarded through guides 5 by 70

100

105

110

forwarding rolls 6. These forwarding rolls are, in the best constructions, and as usual, provided with means for slightly speeding up the cut sheets momentarily, the rolls being provided with cut-away portions 7, a construction usual for such purposes. The sheets are forwarded through guides 8 to the folding and delivering mechanism, which will now be described.

10 In machines constructed in accordance with the present invention there will be provided a folder and associator whereby a product may be produced from one end at each operation thereof, and a product from 15 the other end at every other operation thereof. As shown, this is capacitated to receive the superposed webs and the single web used in the particular machine shown, side by side, and operates to produce a product of 20 sixteen pages from one end at each operation and a product of sixteen pages from the other end at every other operation. While the particular mechanism for effecting this may be widely varied, in the particular construction illustrated there is provided a folding and collecting cylinder which is provided with sheet-taking devices which are supported so that they can be operated at different times longitudinally of 25 the cylinder, thus providing for an unequal collection of the sheets on each side of the cylinder.

In the particular construction illustrated, this cylinder, marked 10 in the drawings, 30 is of the usual hollow type having the flattened portion 11 against which the sheet-taking devices hold the sheets. This cylinder is carried on the shaft 12 journaled in suitable bearings 13 mounted on the frame 40 14 of the machine. This cylinder is driven in any usual manner from the driving shaft 15 of the machine through the usual train of gears, the forwarding rolls 6, before referred to, being also driven through the 45 same train.

The folding and collecting cylinder 10 is, in the particular construction shown, capacitated to receive sheets cut from the superposed webs and from a single web which are 50 forwarded to it side by side and the cylinder is provided with sheet-taking devices operated to deliver a product from the superposed sheets at each revolution and a product from the single sheets at every other 55 revolution. While the sheet-taking devices may be varied, in the particular construction illustrated these sheet taking devices are grippers. In the particular construction illustrated there are provided pairs of 60 grippers 16, 17 and 18, 19. The grippers 16, 17 are located at one side or end of the cylinder and are carried on arms 20, 21, these arms being mounted on rods 22, 23. The rod 22 finds its bearings at one end in 65 a central web 24 of the cylinder, and at

its other end in the cylinder head 25, and the rod 23 is mounted in arms 23^a hung on a rod 23^b which finds its bearings in the web 24 and head 25.

The construction of the grippers and gripper supports is duplicated on the other end of the cylinder, the grippers 18 being mounted in arms similar to the arms 20, 21 which are mounted on a rod 27, the gripper rod 27 finding its bearings at one end in the central web 24 in the cylinder before referred to, and at its other end in the other head of this cylinder 25^a the grippers 19 are mounted similarly to the grippers 17, being carried by a rod 26 mounted in arms 26^a hung on a rod 26^b which finds its bearings in the web 24 and cylinder head 25^a. The gripper-operating rods 22, 23, and 26, 27, are in this way made independent and can be operated to cause the grippers on each end of the cylinder to act at different times.

In the particular construction illustrated, referring to Figs. 3 to 5, the pairs of grippers on each side of the cylinder include a long pair and a short pair. These pairs of grippers on each end of the cylinder will be mounted and operated so as to have the usual opening and closing movement for taking and releasing the sheets. In constructions embodying the invention in its best form, however, for purposes hereinafter referred to, one pair of the grippers on each end of the cylinder will be constructed and operated so that they may be given a movement relatively to the surface of the cylinder against which they grip, that is, a movement away from the path of movement of the surface of the cylinder, the other pair of grippers having their opening and closing movements always in the same place in the path of movement of the surface of the cylinder. In the construction illustrated, the short grippers 16, 18 have no movement relatively to the cylinder except their opening and closing movement, and are operated to open by fixed cams 28, 29 suitably mounted on the frame of the machine at each end of the cylinder, one such cam being provided for each of the gripper rods 22, 27, on which the short grippers are carried, these cams operating the gripper rods through cam rolls 30, 31 carried on arms 32, 33 fast on the gripper shafts 22, 27 and are closed by the usual spring rod construction 32^a and 33^a.

The long grippers 17, 19 are, like the short grippers, operated from independent cams, so that the gripping and releasing on each end of the cylinder may occur at different times, and these long grippers are, furthermore, operated so that in addition to their usual opening and closing movement, they are given a movement relatively to the surface of the cylinder. The construction by which this is effected may be varied, but in

the construction shown the ordinary opening and closing movement is given the grippers through arms 34, 35 on the gripper shafts 23, 26, these arms carrying cam rollers 36, one of which is shown in Fig. 3, and which operate in the grooves 38 of box cams 40, 41, loosely mounted on the shaft 12, before referred to, one of these cams being located on each side of the cylinder.

10 The gripper shafts 23, 26 are, as before stated, carried by arms 23^a, 26^a, which are mounted on the shafts 23^b, 26^b, and mounted on these latter shafts are arms 42, 43 having cam rolls 44 which also run in the grooves 15 38 of the box cams 40, 41. The box cams carry studs 46, 47, to which are connected connecting rods 48, 49, which in turn are connected at 50, 51 to lever arms 52, 53 pivoted on short shafts 54, 55 suitably journaled in the frame of the machine. Also pivoted to the short shafts 54, 55 are cam lever arms 56, 57, which are so arranged as to be connected to the lever arms 52, 53 by bolts 39, and which carry cam rolls 58, 59 20 running in grooves 60 of cams 62, 63, which are mounted on an operating shaft 64 extending across the machine. The cam lever arms 52, 53 are provided with extensions 65, 66 by which these arms can be locked to the frame of the machine by bolts 61 and prevented from operating, as shown in Figs. 30 2 and 3, this being done to permit the machine to be operated as hereinafter described.

In the construction shown in Figs. 1 to 5, 35 and as just described, the parts are illustrated as operated so that a product is folded off from the left hand end of the cylinder at each rotation thereof, and a collected product is folded off from the right hand 40 end at every other rotation thereof. In other words, in the construction shown in these figures, and as so far described, the cylinder is acting as a folding-off cylinder at one end and a collecting cylinder at the 45 other at each rotation, and as a folding-off cylinder on both ends on every other rotation. When this construction is used, the parts are as shown in Figs. 3 and 4, Fig. 3 showing the parts as positioned at the left hand end of the cylinder, and Fig. 4 showing them as positioned at the right hand end of the cylinder. When the cylinder is thus operating to effect this, the cam lever arm 52, shown in Fig. 3, is locked, so that the 50 gripper operating cam 38 is not shifted and the long set of grippers have simply an idle opening and closing movement, the sheets being taken by the short gripper arms.

The folding-off mechanism by which the 60 sheets are delivered may be varied. In the construction illustrated, this fold-off mechanism includes a rotary sheet carrier 67 (which in the construction illustrated is a cylinder) mounted on a shaft 68 suitably journaled in the frame of the machine. This

delivery cylinder 67 is provided with two folding off or nipping jaws, only one of which is shown, these folding off jaws taking care of the products of cylinder 10. These nipping jaws, marked generally 69, 70 are operated by a cam roll 70 from a movable cam 71 on the shaft 68, it being understood that this construction is duplicated on the other side of the delivery cylinder 67. These folding off jaws coöperate with the 75 usual tucker blades 72 carried by the cylinder 10, only one of which is illustrated, it being understood that there is one on each end of the cylinder. For purposes herein-after specified, one of the cams 71 is shifted 80 to cause the nipping jaws to take at different times through one of the cross over arms 73, 74, these arms being operated from the box cams 40, 41, before referred to, these being proportioned so that when the box cams 85 are in proper position, through the cross over arms, one of the cams 71 will be moved so that it will be in proper position to cause the nipping jaws to take at the right time, as shown in Fig. 3. 90

From the delivery cylinder 67 the products are taken by suitable belts 75 to the usual cross-folding mechanisms 76, only one of which is shown, where they are given their final fold. If desired, stitching mechanisms, one of which is shown in dotted lines marked 77, may be employed for stitching or stapling the products. 95

In machines embodying the invention in its best form, means may be provided for 100 covering the sheets as they advance side by side to the cylinder 10, which are or may be of the usual construction. By the employment of the cylinder 10, constructed as described, the two products which are formed 105 thereon may have covers added by the employment of only two cover feeders and have the inserts added by the use of two inset feeders. The cover feeders may be of the usual construction, and are indicated generally by the numerals 78, 79, these cover feeding mechanisms alternately feeding covers to the product, two such mechanisms being necessary to enable the covers to be fed in at the speed of the production of the 110 product. The inset mechanism is also of the usual construction and is indicated generally by the numerals 80, 81, this inset mechanism being employed as is usual for inserting specially printed sheets. Where, 115 as in the particular construction shown, a product two pages long is being produced and a cover is to be added to this product, which is but one page long, means are provided for taking this cover. These means 120 may be of any suitable character, such as the usual taking pins 82, shown in dotted lines in Fig. 3.

The operation of the machine may be briefly stated as follows, it being understood 125

- that the particular machine shown and described is arranged to produce products of sixteen pages each from both sides of the folder from a web six pages wide and four pages around the cylinder, divided longitudinally into three ribbons, two of which are superposed, the two ply and the single ply webs being forwarded side by side and cut at half turn, that is, into sheet lengths
- 5 two pages long longitudinally of the web. When this product is to be produced, the cylinder 10 acts as a collecting cylinder on one end and as a folding off cylinder on the other end at each revolution. Assuming the
- 10 15 two-ply sheets to be forwarded to the left hand side of the cylinder shown in Fig. 2, the parts will be in the position shown in Fig. 3 for this section of the cylinder. As the two superposed webs form a product
- 20 25 sixteen pages when folded, the cylinder at this end delivers to the delivery cylinder two superposed sheets at each revolution. When this is done, the gripper 16 takes the leading end of the two sheets which are carried around the cylinder and folded off by the nipping jaws 69, the cam 71 being in position to allow the folding off jaws on the left hand end of the cylinder 67 to operate at each revolution, as shown in Fig. 3.
- 30 35 When the machine is thus operated the cam 38 is so positioned that the movement of the grippers 17 is an idle movement, taking place after the grippers have passed out of the path of the leading end of the sheet, so as to leave the short grippers clear to take the sheet.
- As only one sheet is going to the other side of the cylinder, that is, the right hand end of the cylinder shown in Fig. 2, it is necessary to collect from this cylinder two products to produce sixteen pages. This is effected, as before described, by positioning the parts as shown in Fig. 4, in which the cam operating arm 53 is unlocked and free
- 40 45 to be reciprocated by the cam arm 57 and cam roll 59, which acts to shift the cam 41 so as to give the long grippers their proper opening and closing movements. When the machine is thus operating, the long grippers take the leading end of the first sheet and carry it around the cylinder, the short grippers taking the leading end of the next succeeding superposed sheet and acting to carry both the sheets around the cylinder, the long grippers 19 having their opening movement delayed until the short grippers have seized both sheets. The shifting of the cam also, through the cross-over 73 shifts the corresponding cam 71 and causes the folding jaws to be in a position to fold off the product at every other turn of the cylinder, so that a product of sixteen pages is folded off this end of the cylinder at every other revolution thereof.
- 50 55 60 65 While, as shown and described, the left

hand end of the cylinder shown in Fig. 2 folds off at every revolution it will be understood that by arranging the parts as shown in Fig. 4, this end of the cylinder may be used for collecting likewise and a variety of products obtained. For instance, with the webs forwarded as shown, a product of thirty-two pages could be produced at one end of the cylinder and a product of sixteen pages on the other end. Furthermore, if the cylinder was used only as a folding-off cylinder on both ends, a product of sixteen pages could be produced from one end, and a product of eight pages from the other end.

80 The invention has been shown and described in its preferred form, but it is understood that many changes and variations can be made in the particular construction and arrangement of the parts, and that changes may be made in the arrangement and operation of the mechanism whereby a wide variety of products may be produced, and that such changes and variations may be made without departing from the invention.

85 What is claimed is:

1. The combination with means for forwarding a plurality of webs side by side, of sheet-severing means, a single folding and collecting mechanism to which the sheets are forwarded side by side, sheet-taking devices on each end of the folding and collecting mechanism, and means for operating the sheet-taking devices whereby the folder and collector may act to fold off a product on one end and a collected product on the other or a collected product on both ends.

2. The combination with means for forwarding a plurality of webs side by side, of sheet-severing means, a single folding and collecting mechanism to which the sheets are forwarded side by side, sheet-taking devices on each end of the folding and collecting mechanism, means for operating the sheet-taking devices whereby the folder and collector may act to fold off a product on one end and a collected product on the other or a collected product on both ends, and a delivery mechanism.

115 3. The combination with means for forwarding a plurality of webs side by side, of sheet-severing means, a folding and collecting cylinder to which the sheets are forwarded side by side, independent sets of sheet-taking devices on each end of the cylinder, and means for operating the devices whereby they are caused to fold off a product at one end of the cylinder on each revolution and a collected product on the other end of the cylinder at every other revolution thereof.

4. The combination with means for forwarding sheets side by side, of a folding and collecting cylinder capacitated to re-

ceive the sheets side by side, and means for folding off a product from one end of the cylinder at every revolution and from the other end at every other revolution.

5 5. The combination with means for forwarding sheets side by side, of a folding and collecting cylinder capacitated to receive the sheets side by side, means for folding off a product from one end of the cylinder at every revolution and from the other end at every other revolution, and a delivery cylinder for taking the products as they are folded off.

10 6. The combination with means for forwarding sheets side by side, of a folding and collecting cylinder capacitated to receive the sheets side by side, sheet-taking grippers on one end of the cylinder, independent sheet-taking grippers on the other end of the cylinder, and means for operating the grippers to cause a product to be folded off from one end of the cylinder at every revolution and from the other end at every other revolution.

15 7. The combination with means for forwarding sheets side by side, of a folding and collecting cylinder to which the sheets are forwarded capacitated to receive the sheets side by side, independent sets of sheet-taking devices on each end of the cylinder, and means for operating the sheet-taking devices to fold off products from each end of the cylinder at different revolutions thereof.

20 8. The combination with means for forwarding sheets side by side, of a folding and collecting cylinder to which the sheets are forwarded capacitated to receive the sheets side by side, independent sets of sheet-taking devices on each end of the cylinder, means for operating the sheet-taking devices to fold off products from each end of the cylinder at different revolutions thereof, and a delivery cylinder.

25 9. The combination with means for forwarding sheets side by side, of a folding and collecting cylinder, sets of grippers on each end of the cylinder, and actuating cams for operating the grippers to cause them to fold off a product from one end of the cylinder at each revolution thereof and to collect a product on the other end of the cylinder and to fold it off at every other revolution thereof.

30 10. The combination with means for forwarding sheets side by side, of a folding and collecting cylinder, sets of grippers on each end of the cylinder, actuating cams for operating the grippers to cause them to fold off a product from one end of the cylinder at each revolution thereof and to collect a product on the other end of the cylinder and to fold it off at every other revolution

thereof, and a delivery cylinder for taking the products as they are folded off. 65

11. The combination with means for forwarding a plurality of webs of an unequal number of plies, of means for severing sheets from the webs, and a single folder for producing the same product from the sheets severed from each web.

12. The combination with means for forwarding a plurality of webs of an unequal number of plies, of means for severing sheets from the webs, a single folder for producing the same product from the sheets severed from each web, and means for stitching the products. 75

13. The combination with means for forwarding a plurality of webs of an unequal 80 number of plies, of means for severing sheets from the webs, means for assembling covers with the sheets, and a single folder for producing the same product from the sheets severed from each web. 85

14. The combination with means for forwarding a plurality of webs of an unequal number of plies, of means for severing sheets from the webs, means for assembling covers with the sheets, means for assembling inset sheets with the web sheets, and a single folder for producing the same product from the sheets severed from each web.

15. The combination with means for forwarding a plurality of webs of an unequal 95 number of plies, of means for severing sheets from the webs, means for assembling covers with the sheets, means for assembling inset sheets with the web sheets, a single folder for producing the same product from the 100 sheets severed from each web, and means for stitching the products.

16. The combination with means for forwarding a plurality of webs of an unequal number of plies, of sheet-severing means, a 105 folding and collecting cylinder having independent sheet-taking devices on each end thereof, and means for operating the sheet-taking devices to produce the same product from the sheets severed from each web. 110

17. The combination with means for forwarding a plurality of webs of an unequal number of plies, of sheet-severing means, a folding and collecting cylinder having independent sheet-taking devices on each end 115 thereof, means for operating the sheet-taking devices to produce the same product from the sheets severed from each web, and a delivery cylinder.

In testimony whereof, I have hereunto set 120 my hand, in the presence of two subscribing witnesses.

OSCAR ROESEN.
